UNITED STATES PATENT OFFICE.

CHARLES H. CHALMERS, OF MINNEAPOLIS, MINNESOTA.

PRESSURE-CONTROLLED FLUID-FEEDING APPARATUS.

Original application filed August 4, 1922, Serial No. 579,671. Divided and this application filed November 14, 1925. Serial No. 69,099.

This invention relates to an improved pressure controlled fluid feeding apparatus particularly adapted for use in conjunction with liquid fuel burning heating plants and furnaces, and more particularly relates to such an apparatus including an automatically operable pressure controlled device adapted during normal operation of the burner to be inoperative, and automatically operable upon failure of ignition to interrupt the supply of fuel to the burner. This application is a division of my pending application Serial #579,671, filed August 4, 1922.

An object of the invention is to provide such an apparatus comprising a pressure chamber having a connection with a source of fluid supply and also having a discharge or fluid feed pipe leading therefrom to a suitable receiving means such, for instance, as a liquid fuel burner, and the feeding of the fuel from said chamber being automatically controlled by air pressure whereby upon normal operation of the apparatus fluid will be delivered through the feed pipe, and upon abnormal operation the fluid will be returned to its source.

The particular object of the invention, therefore, is to provide an improved pressure controlled fluid feeding apparatus.

Other objects of the invention will appear from the following description and the accompanying drawings and will be pointed out in the annexed claims.

In the accompanying drawings there has been disclosed a structure designed to carry out the various objects of the invention, but it is to be understood that the structure is not confined to the exact features shown as various changes may be made within the scope of the claims which follow.

In the drawings,

Figure 1 is a view illustrating an application of the invention to a liquid fuel burning apparatus;

Figure 2 is an enlarged detail sectional view showing the general construction of the pressure chamber controlling the flow of liquid fuel to the burner; and

Figure 3 is a detail sectional view of a liquid fuel burner.

In the selected embodiment of the invention here shown for purposes of disclosure there is illustrated a liquid fuel burner similar to the structure shown in the above men-

tioned pending application. As shown in Figure 3, an air supply pipe 11 has one end connected to a blower 12, of ordinary construction, and its other end connected to an elbow 13 to which a drip pan 14 is suitably secured. A plurality of sheet metal wings 15 are provided around the drip pan 14 in order to catch liquid oil which may spatter from the target 16 or be outwardly sprayed and not ignited when starting the burner. The target may be supported upon suitable posts 17 as shown.

A nozzle 18 is centrally mounted within the discharge end of the elbow 13 and has a fuel feed pipe 21 leading therefrom through the air pipe 11 and outwardly projecting through the casing of the blower 12 as shown. A gas pilot light may be provided by means of the pipe 22 having its discharge end positioned over the drip pan 14 and its other end connected to a common form of Bunsen mixing valve 23 which has a connection with the gas supply pipe 24 as shown. An overflow pipe 25 also leads from the drip pan 14 to an automatic control device such as the drip bucket 26 having a rod 27 connecting it with a pressure controlled fuel feeding apparatus, which will hereinafter be described. The blower 12 may be operated by such means as the motor 28 shown in Figure 1.

In the operation of liquid fuel burners, it is desirable that means be provided for automatically controlling the flow of fuel oil to the nozzle 18 of the burner whereby, upon normal functioning of the apparatus, the feeding of fuel oil to the burner will be continuous, and upon abnormal functioning of the burner such feeding of fuel oil will be automatically interrupted. The novel pressure controlled fluid feeding apparatus fea-

tured in this invention is particularly adapted for use in connection with liquid fuel burners to control the feeding of the fuel oil to the burner. As shown in Figure 2, this apparatus preferably comprises an oil chamber 29 defined by the annular wall 31 and the top and bottom walls 32 and 33. A fuel discharge or feed pipe 34 leads from the chamber 29, adjacent the upper portion thereof, to a stand pipe 35 having its lower end connected to the fuel feed pipe 21, as shown in Figures 2 and 3. A needle valve 36 is provided within the stand pipe 35 adapted to engage a seat 37 provided in the

lower portion of the stand pipe 35. A pair of lock nuts 38 are mounted upon the upper threaded end-portion 39 of the valve stem 36. A compression spring 41 is preferably 5 interposed between the lower lock nut 38 and the cap 42 mounted upon the upper end of the stand pipe 35. The valve is thereby held in normal open position simply resting upon the spring. By relatively rotating the lock 10 nuts 38 upon the threaded end-portion 39 of the valve stem, the lower end of the stem may be relatively adjusted with respect to the seat 37 to control the flow of fuel oil from the stand pipe into the fuel feed 15 pipe 21.

In the structure here shown, the fuel oil is not pumped directly to the burner nozzle but is pumped to the elevated oil chamber where the oil supplied to the burner may be cut off 20 automatically upon failure of ignition or upon failure of the air supply. In other words, the failure of the air supply will automatically prevent the supply of fuel oil to the burner and even if the air supply is 25 functioning properly and the ignition fails, then the fuel supply will be cut off from the burner. The means provided for delivering the oil to the oil chamber 29 consists of a pipe 43 leading therefrom and having a connection with an upright pipe 44 mounted in a cap 45 seated in a cover plate 46 providing a closure for an oil tank 47, preferably mounted beneath the floor as shown in dotted lines in Figure 1. The pipe 44 downwardly 30 extends into the tank 47 and has a suitable pump, not shown, mounted therein which is operable by means of a motor 48 mounted upon a bracket 49 terminally secured to the upright pipe 44. A suitable gear drive 51 35 connects the motor with the pump shaft 52 mounted within the pipe 44 as shown in dotted lines in Figure 1. The pump motor 48 is preferably connected in parallel with the blower motor 28 for simultaneous operation. The starting and stopping of these 40 motors is preferably automatically effected by means of a thermostatic device, not shown, of ordinary construction, and such as is usually employed in connection with apparatus of this type. A filler pipe 53 is provided by which the tank may be filled, and an air vent 54 is also provided which has the usual venting functions and overcomes any tendency of the air to escape up the 45 filler tank during the filling operation of the tank. It may also be noted that the lower end of the filler pipe 53 is provided with a terminal return bend 55 for a similar 50 purpose.

The means provided in the oil chamber 29 for effecting the automatic cutoff or interruption of the feeding of the fuel oil to the burner nozzle upon failure of ignition or upon failure of the air supply, consists of the 55 maintenance of air pressure within a com-

partment 56 defined by the depending annular flange 57 preferably integrally formed with the top wall 32 of the chamber 29. A tubular extension 58 is provided on the bottom wall 33 of the chamber 29 and upwardly 70 projects within the compartment 56 preferably in axial alignment therewith. An overflow pipe 59 leads from this tubular extension 58 to a T-fitting 61 secured to the blower base by means of a nipple 62 as shown in 75 Figure 1. A pipe connection 63 connects the fitting 61 with the upper portion of the tank 47 so that oil discharging into the pipe 59 will be returned to the tank. It is obvious that any oil pumped into the chamber 80 from the delivery pipe 43 would downwardly escape through the overflow or return pipe 59 as soon as the chamber was filled above the level of the upper end of the tubular extension 58.

Means are provided to prevent, during normal operation of the apparatus, the escape of oil down the return pipe and to cause the oil substantially to fill the outer part of the chamber whereby it flows to the 90 stand pipe 35 through the feed pipe 34. Such escape of the oil, during normal operation, down the return pipe 59 is effected by the maintenance of air pressure within the compartment 56, which air pressure is maintained during operation of the apparatus, by the same blower which forces air past the burner nozzle. The top wall 32 of the chamber is provided with a central bossed aperture through which projects the pipe 100 section or nipple 64. The upper end of the nipple 64 is hermetically joined to the T-coupling 65 whose angled branch 66 is suitably coupled to the housing of the blower in order that operation of the blower air pressure may be maintained within the pressure compartment 56. The function of the air pressure maintained in this compartment is to raise the level of the oil outside the flange 57 so that oil is raised to flow out of the 110 pipe 34. As the pump usually delivers more oil to the pressure chamber 29 than is permitted by the needle valve to pass to the burner, there is generally a constant overflow downwardly through the central return pipe 59 and thus back to the tank. The escape of air pressure from this compartment downwardly through the return pipe is prevented by a trap 67 which permits the 115 building up of the desired amount of pressure in the compartment 56. Therefore, the pumped oil may fill the outer portions of the chamber and flow through the pipe 34 to the stand pipe 35. It will thus be obvious that if the air pressure is reduced in 120 the compartment 56 so that the oil may rise therein above the end of the tubular extension 58, the oil will find outlet through the return pipe and will drain the oil chamber below the level of the pipe 34.

Thus, if the pump motor 48 is in operation and for any reason air pressure is not delivered by the blower, it is obvious that the oil would be discharged from the burner 5 nozzle without being atomized or sprayed. However, the failure of the blower to force air to the burner nozzle likewise entails the absence of air pressure in the compartment 56. Thus, the fuel oil supply is automatically 10 interrupted at the oil chamber and the supply to the burner is cut off.

Another contingency which must be guarded against occurs when the pump motor is in normal operation and the blower 15 normally operates so that there is air pressure in the compartment 56 and the oil is delivered to the nozzle and is properly sprayed or blown against the target. Such contingency is the failure of the ignition of 20 the sprayed fuel oil. Means are provided in this novel apparatus to cut off the fuel supply upon the occurrence of such contingency. The unignited liquid fuel is blown outwardly from the nozzle and falls to the 25 drip pan 14 and is retained therein to find outlet through the overflow pipe 25. This overflow pipe 25 conveys this unconsumed oil and delivers it to the bucket 26 which 30 preferably is of cast metal and has an integral upstanding post 68 by means of which the bucket is suspended by the rod 27 from an arm 69 of a lever having a pivotal mounting on the pin 71 borne by ears projecting from the top 32 of the oil chamber. 35 The other arm 72 of the lever is preferably provided with a weight 73 sufficient to maintain the empty bucket in the raised position shown in Figure 2.

The upper end of the T-coupling 65 is 40 open and a closure for this open end is carried by the arm 72 of this bucket lever. A suitable form of closure is provided by means of a gasket 74 which may be suitably secured to the under face of the lever arm 45 72. Leather has been found to be a suitable material out of which to form this gasket. When the bucket is in its raised position, the gasket 74 is held by the depressed arm of the lever closely against the open end of the 50 coupling 65 and thereby hermetically seals this open end. However, when oil overflows from the drip pan through the pipe 25, and collects in the bucket 26 the added weight of the oil will rock the lever raising 55 the weighted arm 72 and thereby opening the coupling 65 whereby the pressure compartment 56 is opened to the atmosphere. In such event, the oil level in the oil chamber descends below the pipe 34. In normal 60 operation of this automatic control, the oil level will be as shown in Figure 2, wherein the oil in the oil chamber, pipe 34, and stand pipe 35, is only under atmospheric pressure, the stand pipe 35 having an air vent 75; while the pressure in the compart-

ment 56 is equal to the atmospheric pressure plus the pressure equal to that of a column of oil in the stand pipe above the oil level in the chamber. The oil pump is so proportioned and actuated that it normally delivers oil to the oil chamber in a quantity equal to the maximum capacity of the burner. Therefore, during normal operation of the apparatus at capacity below burner maximum, the surplus oil runs down the pipe 59. The amount of oil permitted to be delivered to the burner nozzle is predetermined by adjustment of the needle valve 36. As a practical matter, surplus oil is running down the pipe 59 substantially all 80 during operation of the device.

I claim as my invention:

1. A pressure controlled fluid feeding apparatus including a fluid chamber, fluid supply and discharge pipes connected therewith, an air intake also connected with the chamber, a flange within said chamber encircling the air intake, said flange co-operating with the fluid level to define a pressure chamber within said fluid chamber, a fluid return pipe communicating with said pressure chamber, and means adapted upon normal operation of the apparatus to maintain a pressure in said pressure chamber to prevent the return of the fluid from said fluid chamber to its source and to cause it to be discharged from said fluid chamber through said discharge pipe.

2. A device of the class described including an oil chamber having intake and outlet pipes connected therewith, an air intake in the upper wall of the chamber extending downwardly into the chamber, an overflow pipe connected with the bottom wall of said chamber and extending upwardly therefrom into the chamber, said overflow pipe being of smaller diameter than said air intake and terminally extending into the air intake.

3. A pressure controlled liquid fuel feeding apparatus including an oil chamber, oil supply and discharge pipes connected therewith, an annular flange arranged within said oil chamber and depending from the upper wall thereof, a tubular extension projecting upwardly from the bottom wall of the chamber and having a connection with an overflow pipe, the upper end of the tubular extension terminating above the lower edge of the annular flange, an air inlet communicating with the chamber defined by the depending annular flange adapted upon normal operation of the apparatus to maintain a pressure in said chamber to lower the oil level therein, and to cause it to raise in said oil chamber whereby it may be discharged through said discharge pipe.

4. A pressure controlled liquid fuel feeding apparatus including an oil chamber, oil supply and discharge pipes connected therewith, an annular flange arranged with-

in said oil chamber and depending from the upper wall thereof, a tubular extension projecting upwardly from the bottom wall of the chamber and having a connection with an overflow pipe, the upper end of the tubular extension terminating above the lower edge of the annular flange, an air inlet communicating with the chamber defined by the depending annular flange adapted upon normal operation of the apparatus to maintain a pressure in said chamber to lower the oil level therein and to cause it to rise in said oil chamber whereby it may be discharged through said discharge pipe, and means for automatically releasing the air under pressure from said defined air chamber to interrupt the flow of oil through said discharge pipe and to cause it to be discharged into said return pipe.

5. A pressure controlled liquid fuel feeding apparatus including an oil chamber, oil supply and discharge pipes connected therewith, a depending annular flange on the upper wall of said oil chamber centrally disposed within the chamber, a pressure chamber within said oil chamber defined by said flange and the oil level confined within said flange when air is delivered thereto under pressure, an oil return pipe communicating with said pressure chamber, an air supply pipe adapted upon normal operation of the apparatus to maintain a pressure in said pressure chamber whereby the oil delivered to said oil chamber will be discharged therefrom through said discharge pipe, an air discharge opening for said pressure chamber, and means for normally closing said opening and adapted upon abnormal operation of the apparatus to permit the escape of air from said pressure chamber, thereby interrupting the flow of oil through said discharge pipe and causing it to overflow into said return pipe to be delivered to its source.

6. A pressure controlled liquid fuel feeding apparatus including an oil chamber, oil supply and discharge pipes connected therewith, an annular flange on the upper wall of the chamber extending downwardly into the chamber, an oil return pipe communicating with said oil chamber and extending upwardly therein and partially encircled by said flange, an air supply pipe adapted upon normal operation of the apparatus to maintain a pressure in the chamber defined by said flange and the level of the oil therewithin, whereby the oil delivered to said oil chamber will be discharged therefrom through said discharge pipe, an air discharge opening for the pressure chamber defined by said flange, and means for normally closing said opening and adapted upon abnormal operation of the apparatus to permit the escape of air from said pressure chamber, thereby interrupting the flow of

oil into said discharge pipe and causing it to overflow into said return pipe to be delivered to its source, said means comprising a weighted arm having a connection with a drip bucket wherein unignited fuel oil may be delivered from a burner and the weight of said oil causing said arm to oscillate to open said opening.

7. In a liquid fuel heating apparatus, the combination of a fuel nozzle, an air supply for the nozzle to spray the fuel, a source of liquid fuel connected to the nozzle, means to direct fuel through the connection, means interposed between the nozzle and source and adapted to return the directed fuel to the source, pressure means connected with an air supply and adapted, during normal operation of the apparatus, to render said return means substantially inoperative, and automatically operable upon failure of ignition to permit said return means to operate whereby the fuel supply to the nozzle is stopped.

8. In a liquid fuel heating apparatus, the combination of a fuel nozzle, an air supply for the nozzle to spray the fuel, a source of liquid fuel connected to the nozzle, means to direct fuel through the connection, means interposed between the nozzle and source and adapted to return the directed fuel to the source, pressure means connected with an air supply and adapted, during normal operation of the apparatus, to render said return means substantially inoperative, and a drip bucket having a connection with said pressure means and automatically operable by the accumulation of sprayed fuel therein, upon failure of ignition, to permit said return means to operate whereby the fuel supply to the nozzle is stopped.

9. In a liquid fuel apparatus, the combination of a fuel nozzle, an air supply for the nozzle to spray the fuel, a source of liquid fuel connected to the nozzle, means to direct fuel through the connection, a chamber in said connection between the nozzle and source, an outlet in said chamber adapted to return the directed fuel to the source, means in said chamber cooperating with the oil level to define an air compartment in the chamber adapted, when under pressure, to render said outlet substantially inoperative, means to create air pressure in said compartment during normal operable operation of the apparatus, and means to prevent air pressure in the compartment upon failure of ignition whereby fuel supply to the nozzle is stopped.

10. In a liquid fuel heating apparatus, the combination of a fuel nozzle, an air supply for the nozzle to spray the fuel, a source of liquid fuel connected to the nozzle, means to direct fuel through the connection, a chamber in said connection between the nozzle and source, an outlet in said chamber adapt-

- ed to return the directed fuel to the source, a depending flange in said chamber cooperating with the fuel level to define an air compartment in the chamber adapted, when under pressure, to render said outlet substantially inoperative, means to create air pressure in the compartment during normal operation of the apparatus, an escape port for said compartment, a closure therefor normally in seated port-closing position, and means to unseat said closure upon failure of ignition whereby the air pressure in the compartment is reduced and the fuel supply to the nozzle is stopped.
11. In a liquid fuel heating apparatus, the combination of a fuel nozzle, liquid fuel and air connections to the nozzle, means to supply air to the nozzle thereby to spray the liquid fuel, a fuel chamber above the fuel source, means to supply fuel to the chamber from said source, a circular depending flange in said chamber cooperating with the fuel level to define an air compartment within the chamber and open at its lower end, a trapped return conduit extending from within said compartment downwardly through the fuel chamber to the source, said nozzle fuel connection communication with the chamber above the lower end of the air compartment, means normally to maintain air pressure in the compartment thereby to raise the fuel level in other portions of the chamber above said return conduit and whereby fuel may flow out said connection to the nozzle, and means automatically operable to release the pressure in the air compartment upon failure of ignition, whereby the flow of fuel to the nozzle is stopped and the fuel is permitted to return to the fuel source.
12. In a liquid fuel heating apparatus, the combination of a fuel nozzle, liquid fuel and air connections to the nozzle, means to supply air to the nozzle thereby to spray the liquid fuel, a fuel chamber above the fuel source means to supply fuel to the chamber from said source, a depending flange within the chamber cooperating with the oil level to define an air compartment within the chamber, a trapped return conduit extending from within said compartment downwardly through the fuel chamber to the source, said nozzle fuel connection communicating with the chamber above the upper end of the return conduit, means normally to maintain air pressure in the compartment thereby to raise the fuel level in other portions of the chamber above said return conduit end whereby fuel may flow out said connection to the nozzle, an escape port for said compartment, a closure therefor normally in seated port-closing position, and means to unseat said closure upon failure of ignition, whereby the air pressure in the compartment is reduced and the fuel supply to the nozzle is stopped.

In witness whereof, I have hereunto set my hand this 12th day of November, 1925.

CHARLES H. CHALMERS.
